Primary Examiner — Mary Ann Calabrese*Assistant Examiner* — Katelin G Kloberg(74) *Attorney, Agent, or Firm* — Harness, Dickey & Pierce, P.L.C.; Anthony G. Fussner(57) **CLAIM**

The ornamental design for a medical sleeve, as shown and described.

DESCRIPTION

FIG. 1 is a top, rear, left side perspective view of a medical sleeve, showing my new design with an environment of use;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is an interior view of the medical sleeve, shown in a flat configuration.

In the drawings, the pet shown in broken lines of the type dash-dot-dot-dash depict environment subject matter only and form no part of the claimed design. The broken lines of the type dot-dot-dot depict claimed stitching.
